TIME SWITCH

Harvey L. Emery, Bloomfield, Ind.

Application April 24, 1946, Serial No. 664,489

4 Claims. (Cl. 200—34)

1

This invention relates to a time switch for an electric circuit and is particularly applicable to washing machines, electric toasters, waffle irons, electric stoves, and other home appliances, and which is readily operable by manual means to predetermine the interval of delayed action desired by the operator.

The invention has to do with a device operating somewhat on the dashpot principle, but wherein its delaying action is controlled by frictional resistance. Thus the effect of gravity is negligible, whereby the switch will operate in any position independent of gravity, and its operation is independent of all elevational and barometric pressure variations.

It is an object of the invention to effect an improvement over the conventional dashpot device and to lessen the possibility of failure peculiar to the conventional type of switch. This is accomplished by biasing the contact member against frictional resistance.

It is a further object of the invention to produce a device which is simple in construction and, therefore, inexpensive to produce.

Another object of the invention resides in the arrangement of a combination snap and delayed action switch permitting the operator to employ either feature as and when he desires.

The full nature of the invention will be understood from the accompanying drawings and the following description and claims.

Fig. 1 is a plan view of the time switch.

Fig. 2 is a longitudinal sectional view thereof taken on the line 2—2 of Fig. 1.

Fig. 3 is a bottom plan view of the time switch.

Fig. 4 is a side elevation view of a modification of the time switch with parts broken away.

Fig. 5 is a vertical section view thereof.

Fig. 6 is a plan view thereof taken on a line 6—6 of Fig. 5.

Fig. 7 is a section view thereof taken on a line 7—7 of Fig. 6.

In the drawings for the purpose of illustrating an application of the invention, the delayed action or time switch is shown housed in a casing 10 having a removable cover plate 11 suitably secured in position by means of screws.

The switch mechanism comprises a confining friction member, here shown as a cylindrical tube 12, which is open at both ends and is secured to the cover plate by means of screws 13 and 14. Slidable within the tube is an expansible friction element here shown as a plunger 15, connected to a shaft 16 which is supported at one end by the bearing 17 secured to the cover plate

2

by means of screw 18. The shaft is secured to a supporting bracket 19, which has a control arm 20 extending through a slot 21 in the cover plate, by the set screw 23. To the end of the arm 20 there is secured a manually operable knob 24 by means of anchor screw 25.

Threaded to the shaft near one end thereof and abutting a washer 22 which separates it from the plunger 15, there is a compression nut 26 which may be rotatably adjusted by the operator through the slot 27 in the casing either to compress or release the plunger to thereby increase or decrease the frictional resistance of the plunger.

Biassing the expansible plunger towards one end of the friction tube are tension springs 30 and 31 which are supported at one end by the base 32 of rack 33 and at the other end by bracket 34 which is secured to the cover plate by screw 35.

The base 32 of rack 33 has an aperture intermediate both ends through which protrudes the reduced end 28 of the shaft. The rack 33 is held in mesh by boss 29 with pinion 35 which controls the movement of the time indicator 36.

As the operator manually adjusts the stroke of the plunger 15 through the medium of knob 24 he causes it to move away from the contact strip 37 against the resistance of the springs 30 and 31. When the operator releases the knob, the tension of the springs overcomes the frictional resistance between the expansible friction plunger and the tube 12 and causes said plunger to move rearwardly towards the switch control elements.

Electric contact elements 38, 39, 40, and 41 are suitably insulated and adapted to be electrically connected into any electric circuit. Contact strip 37, preferably formed of spring metal, is secured to terminal 39 and is engageable with terminal 38. As the expansible friction plunger approaches the contact strip, the means operatively connected with it, here shown as an insulated stem 42 at one end of the shaft, engages with the contact strip and causes it to become disengaged from terminal 38 thereby breaking the circuit.

Figs. 4, 5, and 6 show a modified form of the invention which combines snap and delayed action means. A casing 43 is secured to a wall hanger 44 which has a slot therein permitting an over center operable cam switch 45 supported by bearing 46 and pivoted at 47, to move freely to and from therein.

The expansible friction element, here shown as a plunger 48, has frictional engagement with the inner walls of a confining member, here shown as a cylindrical tube 49, which is open at one end. The plunger is secured to a shaft 50, which is

freely slideable within said tube and mounted in an insulated bearing plate 51, which is separated from the plunger by bushing 52. The frictional resistance of the plunger may be increased or decreased at will through an adjustment of nut 53. Springs 54 and 55 cause the plunger to move against its frictional resistance.

Electric contact elements 56, 57, 58, and 59 are adapted to be electrically connected into any electric circuit. Contact strip 60 is secured to plate 61 and is engageable with plate 62.

When it is desired to employ the snap action feature of this modification, the operable cam switch is moved by the operator to the position shown in Fig. 4. The cam face engages the shaft 59 and forces the insulated bearing plate downwardly out of engagement with contact strip 60 permitting said contact strip to become engaged to plate 62 thereby completing the circuit.

When the operator desires to employ the delayed action feature of the modification, he moves the cam switch member 45 forwardly as far as it will go. The cam face 63 of the cam switch member engages the shaft 59 and forces it downwardly against the resistance of the springs 54 and 55. The operator then moves the switch member back to the position shown in Fig. 5. The tension of the springs gradually overcomes the frictional resistance of the plunger and causes the insulated bearing plate 51 to engage the contact strip 60 and disengage said strip from plate 62, thereby breaking the circuit.

I claim:

1. In an electric time switch including a housing, a stationary electric contact on said housing, a movable contactor engageable therewith biased in one direction under tension of a biasing spring and an actuator for moving said contactor in the opposite direction, the combination therewith of a confining tubular member having an internal friction surface, a friction element having a radially expansible head of friction material movable within said tubular member in restraining frictional engagement with its friction surface, and means operably connecting said friction element with said contactor whereby upon being moved in a direction opposed to the bias of said contactor the frictional resistance thereof will delay its movement from contact engaging to contact breaking positions.

2. In an electric time switch including a housing, a stationary electric contact on said housing, a movable contactor engageable therewith biased in one direction under tension of a biasing spring and an actuator for moving said contactor in the opposite direction, the combination therewith of a cylindrical well formed in said housing, said well having a confining and restraining friction surface, a friction element having a head of expansible friction material movable within said well in frictional engagement with its confining and restraining friction surface, and means operably connecting said friction element with

said contactor whereby upon being moved in a direction opposed to the bias of said contactor the frictional resistance thereof will delay its movement in the biased direction.

3. In an electric time switch including a housing, a stationary electric contact on said housing, a movable contactor engageable therewith biased in one direction under tension of a biasing spring and an actuator for moving said contactor in the opposite direction, the combination therewith of a confining tubular member having an internal friction surface, a friction element having a radially expansible head of friction material movable within said tubular member in restraining frictional engagement with its friction surface, regulating mechanism in engagement with opposite sides of said friction head to axially compress it in a direction to vary its effective diameter relative to said tubular member for regulating the time delay from actuated to actuating position, and means operably connecting said friction element with said contactor whereby upon being moved in a direction opposed to the bias of said contactor the frictional resistance thereof will delay its movement in the biased direction.

4. In an electric time switch including a housing, a stationary electric contact on said housing, a movable contactor engageable therewith biased in one direction under tension of a biasing spring and an actuator for moving said contactor in the opposite direction, the combination therewith of a restraining member on said housing having a friction surface, a friction element movable relative to said member in restraining frictional engagement with its friction surface, a time setting device in operative engagement with the biasing spring to vary the tension thereof relative to the frictional resistance between said friction element and restraining member, and means operably connecting said friction element with said contactor whereby upon being moved in a direction opposed to the tension of said biasing spring the frictional resistance of said member will delay its movement in the biased direction.
